UNITED STATES PATENT OFFICE

WILSON A. JAICKS, OF CHICAGO, ILLINOIS

APPARATUS FOR MIXING CONCRETE

Application filed June 3, 1931. Serial No. 541,923.

My invention relates to improvements in apparatus for mixing concrete of the same general type as is shown in my co-pending application Ser. No. 523,709 wherein the batch is partially mixed in one mixer, then discharging therefrom in an incompletely mixed condition and thereafter charged into a second mixer which further mixes the concrete and which may thereafter discharge concrete either to another mixer, to a storage or conveying zone or member or directly to the work as the case may be. Other objects will appear from time to time throughout the specification and claims.

My invention is illustrated in the accompanying drawing, wherein—

Figure 1 is a side elevation of the preferred form of my device;

Figure 2 is a detail side elevation of a modified form;

Figure 3 is a plan view of the device shown in Figure 2;

Figure 4 is a section along the line 4—4 of Figure 2.

Like parts are indicated by like characters throughout the specification and drawing.

Number 1 mixer is shown on the left. It comprises a mixing drum A driven by motor A¹ supported by means of driving rollers A² on the platform A³ which in turn is supported on the crawler running gear A⁴ which may also be driven and controlled from the motor A¹ by any suitable conventional means, the details of which are not here shown. The unmixed concrete consisting of sand, gravel and crushed rock, cement and water is placed in drum A, the chute A⁵ providing a convenient means for inducing the aggregate. Extending forwardly away from the discharge end of the drum A is a supporting framework A⁶ having a track A⁷ upon which is mounted a belt conveyor ladder A⁸ which ladder is provided with rollers A⁹ adapted to travel along the track A⁷ so that the ladder may either be moved out into the inoperative position shown in full lines or in into the operative position shown in dotted lines. When

in the full line position rotation of the drum

merely results in mixing the concrete. When in the dotted line position if the belt conveyor is operated as it must be, the material being mixed in the drum, is deposited on the belt conveyor and fed forwardly into the drum and in view of the fact that the drum is rotating only a very few seconds elapses from the time that the belt conveyor is moved into the drum to the time when the entire contents of the drum have been deposited on the belt conveyor and carried away by it.

No. 2 mixer is at the right. It comprises a drum B driven by motor B¹ supported by motor driven rollers B² from the platform B³ projecting toward the rear. It carries a fixed ladder B⁶ on which is mounted a belt conveyor B⁷, which belt conveyor discharges by means of the chute B⁸ into the drum B. The movable tie bars B⁹ join the platforms A³ and B³ into fixed relation with the belt conveyor B⁷ beneath and adapted to receive the discharge from the belt conveyor A⁸ so that concrete discharged from the drum A may be caught by the belt conveyor A⁸, conveyed by it and discharged to the conveyor B⁷ which in turn feeds it to the drum B. The belt conveyor B⁷ is driven from the motor B¹ by means of the belt B¹⁰. The belt conveyor A⁸ is driven from the motor B¹ by means of the belt B¹¹. When the belt conveyor A⁸ is withdrawn from the drum A the belt B¹¹ remains slack as indicated and does not transmit power. When the conveyor A⁸ is thrown into the drum A located in position by any suitable means, the belt B¹¹ is tight and causes operation of the belt conveyor A⁸.

The tie rod B⁹ constrains the two mixers into a position such that the belt conveyors are in proper working relation one with the other. Under some circumstances, however, the tie bars may be omitted and in this case the moving and positioning of the two mixers becomes slightly more difficult and the operator must manipulate them more carefully to insure that they are spotted in proper relation to permit the belt conveyor A⁸ to discharge onto the belt conveyor B⁷. Normally the two mixers are arranged in a

line parallel with the axis of the road or work. Under some circumstances, however, they might be differently related out of line. Their axes might be parallel or inclined, 5 they might be perpendicular to each other, they might be distinctly out of line or arranged in any way suitable and convenient for manipulation of the mixers, discharge of the finished concrete and supply of the 10 raw material, it being only necessary that they be so related that the belt conveyor or other convenient means from mixer No. 1 will always discharge onto the conveying means, whatever they may be adapted to 15 feed material to mixer No. 2. Of course, if the belt conveyor of mixer No. 1 is to be driven from the motor associated with mixer No. 2, it is necessary that the relations be such that drive is possible. In the preferred 20 form shown in Figure 1, they must be in line but if other flexible driving means were provided or if motor A¹ drove belt conveyor A² the driving means would impose no limitations on the relative positions 25 of the two mixers.

In the modified forms shown in Figures 2, 3 and 4, C is a fixed belt conveyor ladder. It is driven from the shaft, which carries the rollers A² by means of a bevel gear and 30 shaft power system C¹ to the shaft C² which by means of a sprocket chain C³ drives the belt. In this case the ladder and the belt conveyor always project into drum No. 1. As long as the shield C⁴ on its rollers C⁵ is 35 located inside the drum as indicated on Figure 2, the material as it is picked up by the drum or by the blades in the drum, carried up and allowed to fall, will strike the shield and slide on it so as not to be deposited onto 40 the belt conveyor. If the shield is drawn to the left into the dotted line position, it will no longer protect the belt conveyor and the concrete will be dropped onto the belt conveyor and by it discharged to drum No. 45 2.

It will be understood, of course in operating the device, the raw materials including water are introduced into mixer No. 1 and there mixed for a length of time less 50 than the total mixing time, then discharged from mixer No. 1 into the conveying apparatus and by it conveyed to mixer No. 2, where either the concrete may stay long enough to complete its mixing or may stay 55 a length of time less than the total mixing time required, in which latter case, material will be taken from drum No. 2 to some other suitable point for further treatment either by means of a third drum or other suitable 60 apparatus.

The relation between the capacity of the mixer, the rate at which material is discharged from the mixer, the capacity of the conveyor and the rate at which the material 65 is discharged from the conveyor must be

such that as soon as the conveyor is brought into working relation with drum No. 1, it carries the mixed material away from that drum as fast as the drum discharges it so that the discharge from the drum causes 70 no delay in the cycle of operation. Normally this length of time is only a few seconds. The material discharged from the drum carried by the belt conveyor will immediately under ordinary conditions be discharged into the second drum. The belt conveyor may be so long that the entire batch may be discharged into the belt conveyor system before it starts to be fed onto the second drum or it may be so short that 75 the second drum begins to receive the partially mixed material before the first drum has finished discharging but in either event the operation must be so timed that as soon as the material has been discharged from 80 drum No. 2, material from drum No. 1 will commence to reach drum No. 2 and as soon as material has been discharged from drum No. 1, raw material will begin to be added to it but there must be no overlap. It is 85 necessary that all the material be out of drum No. 1 before any new material is put in and all the material be put out of drum No. 2 before any new material is put in. 90

I claim:

1. A concrete mixing apparatus comprising a plurality of mixing drums, separate supporting and operating means therefor, a belt conveyor system interposed between them comprising a separate framework 100 mounted on each drum supporting means, a separate belt conveyor mounted on each framework, one belt conveyor adapted to receive material from the first drum and discharge it to the other conveyor, which conveyor discharges material to the second drum, the first conveyor being movable as a unit along a generally horizontal path toward and from the first drum whereby when moved toward the drum it projects thereinto and is adapted to receive material, drive means for said conveyors mounted on the support for the second drum, and a discontinuous driving connection between the first conveyor and the drive means and means for causing its operation when the first conveyor is projected into its associated drum. 110

2. A concrete mixing apparatus comprising a plurality of mixing drums, separate supporting and operating means therefor, a belt conveyor system interposed between them comprising a separate framework mounted on each drum supporting means, a separate belt conveyor mounted on each framework, one belt conveyor adapted to receive material from the first drum and discharge it to the other conveyor, which conveyor discharges material to the second drum, the first conveyor being movable as a unit along a generally horizontal path to 120

- ward and from the first drum whereby when moved toward the drum, it projects thereinto and is adapted to receive material, drive means for said conveyors mounted on the 5 support for the second drum, and a discontinuous driving connection between the first conveyor and the drive means operative only when the first conveyor is projected into its associated drum, the driving means for said 10 first conveyor including a belt, a pulley carried by the supporting means for the second drum, a pulley associated with the first conveyor, the belt being adapted to be loose and so have no driving effect when the conveyor 15 is out of register with the drum but to be tight and drive the conveyor when the conveyor is in the drum and simultaneously to limit the inward excursion of the conveyor toward the drum.
- 20 3. A concrete mixing apparatus comprising a plurality of mixing drums, separate supporting and operating means therefor, a belt conveyor system interposed between
- them comprising a separate framework mounted on each drum supporting means, a separate belt conveyor mounted on each framework, one belt conveyor adapted to receive material from the first drum and 70 discharge it to the other conveyor, which conveyor discharges material to the second drum, the first conveyor being movable as a unit along a generally horizontal path toward and from the first drum whereby when moved toward the drum it projects thereinto and is adapted to receive material, drive means for said conveyors mounted on the support for the second drum, and a discontinuous driving connection between the first 75 conveyor and the drive means operative only when the first conveyor is projected into its associated drum, the capacity of the belt conveyor system being such that it can receive and hold at one time the entire contents of the first drum. 80
